UNITED STATES PATENT OFFICE

ROY J. TAYLOR, OF ASHTABULA COUNTY, OHIO, ASSIGNOR OF ONE-HALF TO THE
AMERICAN GYPSUM CO., OF PORT CLINTON, OHIO, A CORPORATION OF OHIO
METAL CLIP FOR HOLDING EXPANDED OR OTHER METAL ANGLE CORNERS IN WALLS

Application filed March 28, 1931. Serial No. 525,925.

This invention relates to corner structures including a metal clip specially designed for holding expanded or other metal angle corners in walls.

5. It is one of the objects of the invention to provide a handy clip which may be pressed in between the joints of sheet rock or plaster board by the thumb of the worker without the use of hammer or nails.

10. This clip is not fastened to the joist or studding and any shrinkage or settling of such joists or studding will not affect the board over which the plaster is spread and hence will eliminate to a material extent the cracking of the plaster in the corners of a wall.

15. Another advantage of the invention is that the application of this clip insures a neat clean job of plastering.

20. Various other objects and advantages will become apparent from a consideration of the description following, taken in connection with the accompanying drawing illustrating an operative embodiment thereof.

25. In the drawing:

Figure 1 is a perspective view of a fragmentary portion of a wall with the metal corner held in position by the clip; Fig. 2 is an enlarged view of a fragment of Fig. 1; 30 Fig. 3 is a plan view of the clip; Fig. 4 is a side elevation of Fig. 3; Fig. 5 is an end view of Fig. 3.

Referring specifically to the drawing, the studding is indicated at 10 with the plaster board 11 and metal corner 12 which has a plurality of diamond shaped apertures 13 through one of which the prong 14 of the clip is pushed, the clip comprising an angular plate the parts 15 and 16 of which lie 35 along the outer surface of the metal corner 12 and holds it pressed against the plaster board 11. A plurality of these clips may be used along the length of the metal corner.

40. The plate is angular in outline, with a corner at 17, at one edge of which the prong 14 is bent down at a right angle to the plane of the plate, and this prong is driven or pressed into the board 11 to clip or hold the corner angle in position, so that the plate 45 lies closely against the angle and is covered 50

by the plaster. The clip and angle therefore are not disturbed or distorted by any settling or shrinking of the studding, which otherwise might cause cracking of the plaster.

55

I claim:

The combination, in a corner structure for buildings, of studding, plaster board thereon, a reticulated metal corner angle fitting against the board, said metal having diamond shaped openings, and clips fitting 60 against the metal angle, each clip consisting of a flat metal plate having a corner angle and a prong bent down along one edge of the angle between the ends of the plate and extending diagonally through one of said openings in a direction transverse to the length 65 of the metal corner angle.

In testimony whereof, I do affix my signature.
